UNITED STATES PATENT OFFICE.

WILLIAM L. PAUL, OF SOUTH BEND, INDIANA. ASSIGNOR TO OLIVER CHILLED PLOW WORKS,
OF SOUTH BEND, INDIANA.

CULTIVATOR.

No. 882,957.

Specification of Letters Patent. Patented March 24, 1908.

Application filed January 15, 1907. Serial No. 352,442.

To all whom it may concern:

Be it known that I, WILLIAM L. PAUL, a resident of South Bend, in the county of St. Joseph and State of Indiana, have invented 5 certain new and useful improvements in Cultivators; and I do hereby declare the following to be a full, clear, and exact description of the invention, such as will enable others skilled in the art to which it appertains to make and use the same.

My invention relates to improvements in cultivators, an object of the invention being to provide improvements upon the structure disclosed in Patent No. 836,779 granted No-

vember 27th, 1906.

A further object is to provide an improved implement supporting frame, pivotally connected with a pole, and movable angularly relative to the pole by means of the pivoted 20 seat bar.

With these and other objects in view, the invention consists in certain novel features of construction and combinations and arrangements of parts as will be more fully 25 hereinafter described and pointed out in the claims.

In the accompanying drawings, Figure 1 is a fragmentary plan view illustrating my improvements. Fig. 2 is a view in side elevation thereof, and Figs. 3 and 4 are fragmentary plan and side views illustrating a modification.

1 represents an arch axle having stubs at its ends supported in the hubs of traction 35 wheels 2. A bracket 3 is supported centrally on the arch axle 1 and a double seat bar 4 extending longitudinally of the frame, and straddling the bracket 3, is pivotally connected thereto between the ends of the seat 40 bar, by a pivot pin 5 projecting through both members of the seat bar and through lugs 6 on the bracket. A driver's seat 7 is secured on the rear end of the seat bar and the forward ends of the double seat bar are disposed above and below a slotted bracket 8 45 on the rear end of pole 9, and a coupling pin 10 is supported in alined openings in the ends of double bar 4 and carries a sleeve 11 located in the slot or bracket 8.

50 An arch 12 has rotary mounting centrally in a sleeve 13 and the latter is provided with a vertical pin 14 pivotally secured in a bearing in pole 9, and the beams 15 of furrow openers 16 are secured to brackets 17 clamped

on bearing sleeves 18 located on the ends of 55 the arch 12.

A frame 19 is secured centrally to bracket 3 and to bearing collars 20 on axle arch 1 and projects forward and is secured to opposite sides of a coupling 21 straddling the pole and 60 pivotally connected therewith by a pivot pin 22. Fore hounds 23 pivotally connect the collars 20 with the brackets and project forwardly beyond the latter. A cross bar 24 pivotally secured between its ends to pole 9. 65 13 is provided at its ends with depending pivotally secured links 25 connected by rods 26 with the forward ends of hounds 23. A notched segment 27 is secured to frame 19, and a lever 28 is pivotally secured to the segment and connected at one end by a chain 29 with the furrow opening gang to elevate the latter when the lever is swung, and a spring-pressed detent 30 is provided on the lever to lock with the segment and secure 70 the lever at various adjustments, and a lever may be provided for each gang or a single lever may operate all the gangs, as may be desired. Bars 31 connect the forward part of frame 19 with the axle stubs to compel the 80 axle to shift with the frame, and stirrups or foot rests 32 are provided on the furrow opening gangs to receive the feet of the operator on the seat.

The operation is as follows:—When pressure is applied on the right stirrup, the seat bar will be moved to the left, swinging the inner end of the pole to the right and through the medium of the several links and hounds, change the angle of the axle, front arch and 90 frame and dispose the furrow opening gangs at an angle to the line of draft as represented by the position of the pole.

In the modification illustrated in Figs. 3 and 4, the forward arch is supported at its 95 ends in bearings 33 at the lower ends of depending rods 34 pivotally connected at their upper ends to a cross bar 35, and the arch between its ends is located in a bifurcated bracket 36 pivotally secured to the pole by 100 a pin 37 and a rod 38 connects the pin 37 with a crank arm 39 on the arch compelling the bracket and arch to swing together.

Other changes might be made in the general form and arrangement of the parts described without departing from my invention and hence I would have it understood that I do not restrict myself to the precise

details set forth but consider myself at liberty to make such slight changes and alterations as fairly fall within the spirit and scope of my invention.

5 Having fully described my invention, what I claim as new and desire to secure by Letters Patent is:—

1. In a cultivator the combination with a frame and a pole having a pivotal mounting thereon, and a seat bar pivotally connected between its ends to the frame and a pivotal connection between the forward end of the seat bar and the rear end of the pole.

10 2. In a cultivator, the combination with an arch axle, of a frame thereon, a pole pivotally connected to the frame, a front arch, connections between said front arch and frame, furrow openers connected with the front arch, and a seat bar pivotally connected 15 with the frame and having pivotal connection with the pivoted pole to move the frame angularly to the pole.

20 3. In a cultivator, the combination with an axle, of a frame thereon, a pole pivotally connected to the frame, a front arch, hounds pivotally connecting the front arch and frame, furrow opening gangs connected to the front arch and carrying foot rests or stirrups, a seat bar pivotally secured to the

frame between its ends and pivotally connected at its forward end to the end of the pole, to swing the frame angularly to the pole.

25 4. In a cultivator, the combination with an axle, of a frame thereon, a pole pivotally connected with the frame, a front arch, hounds pivotally connecting the front arch and frame, furrow opening gangs connected with the front arch, a seat bar pivotally attached to the frame between its ends and pivotally connected at its forward end with 30 the end of the pole.

35 5. An agricultural implement comprising a wheeled frame, a pole pivotally connected forwardly of its rear end with said frame, a seat bar pivotally connected between its ends 45 with the frame and pivotally connected with the pole, a front arch connected with the frame, a connection between said front arch and the pivoted pole, and furrow openers connected with said front arch.

40 In testimony whereof, I have signed this specification in the presence of two subscribing witnesses.

50 WILLIAM L. PAUL.
